E. C. WHITE,
ELECTRICAL CONNECTING AND SUPPORTING DEVICE.
APPLICATION FILED MAY 19, 1920.

1,362,067.

Patented Dec. 14, 1920.

UNITED STATES PATENT OFFICE.

ERNEST CANTELO WHITE, OF NEW YORK, N. Y., ASSIGNOR TO ELECTRIC OUTLET COMPANY, INC., OF NEW YORK, N. Y., A CORPORATION OF NEW YORK.

ELECTRICAL CONNECTING AND SUPPORTING DEVICE.

1,362,067.

Specification of Letters Patent. Patented Dec. 14, 1920.

Application filed May 19, 1920. Serial No. 382,639.

To all whom it may concern:

Be it known that I, ERNEST CANTELO WHITE, a citizen of the United States, residing in the borough of the Bronx of the city 5 of New York, in the State of New York, have invented certain new and useful Improvements in Electrical Connecting and Supporting Devices, of which the following is a specification, reference being had to 10 the accompanying drawing, forming a part hereof.

In the following mentioned copending applications of the present applicant there are 15 shown and described various embodiments 15 of a universal system for electrically connecting and mechanically supporting appliances of various types in outlet receptacles, viz: Ser. Nos. 350,688; 350,689 and 350,690, filed January 10, 1920; Ser. No. 352,087, filed 20 January 17, 1920; Ser. No. 363,419 filed March 5, 1920, and Ser. No. 372,383, filed April 9, 1920. In certain of those cases the electrical connecting and supporting devices are illustrated and described as for 25 ceiling receptacles, while in others of the cases they are shown in connection with wall receptacles. In any event, it is pointed out that the broad idea is the same in that by such devices it is sought to provide means 30 for readily connecting and supporting appliances on a standardized system without requiring special wiring. In some of the devices it is proposed to hold the supporting arms in place in the receptacle by mechanical means, while in some of the other forms such arms are locked in place by the gravity pull of the appliance. The present device falls within the broad invention running 35 through all of said applications but is 40 designed with reference to its application to a ceiling receptacle and to the locking of the supporting arms within the receptacle by means of a gravity pull of the appliance thereon. The invention will be described in 45 detail in connection with one suitable embodiment thereof as shown in the drawing, in which—

Figure 1 is a view in section showing the application of an improved receptacle and 50 supporting arms to a ceiling outlet.

Fig. 2 is a view in transverse section taken through the elements shown in Fig. 1.

Fig. 3 is a view in plan showing one 55 means of supporting the improved receptacle within the outlet box.

Fig. 4 is a detail view in elevation of a terminal member for the improved receptacle.

Fig. 5 is a view in plan of the terminal member shown in Fig. 4.

Fig. 6 is a detail view in transverse section of the same terminal member taken on the plane indicated by the line 6—6 of Fig. 4 and looking in the direction of the arrows.

Figs. 7 and 8 are detail views of suitable 65 supporting ears for the improved receptacle.

In the condition illustrated in the drawing it has been assumed that the improved receptacle is to be applied to a previously installed shallow ceiling outlet box *a* into 70 which lead the main wires *b*. Since the outlet box *a* is so shallow as not to house the improved receptacle, indicated generally at *c* in Fig. 3, it is proposed to support this receptacle below the box *a* and below the 75 surface of the ceiling and then close it by means of a canopy *c'*. The receptacle *c* may be supported from a fixture stud *a'* bolted within the box *a* and having threaded adjustably thereon a nut *a''*. The receptacle 80 *c* which will be described in greater detail hereinafter may have secured to its side walls sheet metal plates *d*, *d'*, from which are struck up ears *d''* to embrace the top and bottom edges of the receptacle *c*, the lower 85 ears *d''* being adapted to receive retaining screws *e* which pass into the receptacle. The plates *d*, *d'* are stamped at the upper ends with key sections *d''* adapted to pass through slots *f* cut longitudinally of a 90 bridge piece *f'* which may be hung on the adjustable nut *a''* of the fixture stud *a'*. From the description given it will be evident that by slipping the key pieces *d''* through the slots *f* and turning them the 95 plates *d* may be readily secured to the receptacle *c* and the unit thus formed may be attached to the fixture stud by passing the bridge over it and setting up on the nut *a''* to a degree sufficient to bring the receptacle in proper relation to the ceiling. A 100 ceiling plate *g* can be secured to the plates *d*, *d'* by means of screws *g'* passing through reversely bent ears *d''* on the plates *d*.

The details thus far described while of 105 importance in constructions of this character do not in themselves constitute essential features of the invention. This has to do principally with the relation between the receptacle and the supporting arms for 110

the electrical appliance. The receptacle *c* may be made up conveniently of three pieces of fiber *c'*, *c''*, *c'''*, bolted together by means of through-bolts *c⁴*. Between these fiber blocks are mounted terminal pieces *h*, *h'* one of which, *h*, is shown in detail in Figs. 4-6.

This terminal plate is of metal and has stamped therein a generally curved channel *h²* which terminates in alignment with an entering slot *c⁵* in the fiber of the receptacle *c*. The inner end of the channel *h²* straightens out so as to provide a generally horizontal portion *h³* for a purpose which will appear. On the terminal plate *h* is supported a spring terminal *h⁴* to receive the terminal arms of an attachment plug of standard form. This spring terminal *h⁴* lies behind a slot *c⁶* formed in the face of the receptacle *c* to receive such a terminal arm. It is evident that parallel terminal arms of attachment plugs can be received in the face of the receptacle *c* through the parallel slots to be employed for receiving the supporting arms of the improved device, one of such slots being indicated at *c⁵*. Accordingly the construction will admit of the use of attachment plugs having arms of either of the standard forms now on the market. The terminal plate *h* is connected to one of the main wires *b* by a binding screw *h⁵*, the other terminal *h'* being similarly connected to the other of the wires *b*.

The invention is primarily concerned with the improved character of the supporting and conducting arms used for connecting the appliance electrically to the source of current and supporting it mechanically within the improved receptacle *c*. The supporting plug is made up of two symmetrical halves *k*, *k'*, each of which comprises a block of fiber to which is secured a curved conductor arm such as *l*, the curvature of which conforms generally to the curvature of the channels in the terminal plates *h*, *h'*. As shown in Fig. 2, for instance, one half *k* of the block has a curved terminal *l* which is secured to the fiber by means of a screw *l'* and is connected in circuit with the wire *m* from the appliance (not illustrated) by a binding screw *m'*. The fiber block may be carried within a metallic shell *n* the lower end of which terminates in a hook *n'* having formed therein a curved slot *n²*. The other half *k'* of the block is made up in exactly the same manner and on the lower end of its metallic shell *o* there is carried a hook *o'* which is similar to the hook *n'* but, when the two halves *k*, *k'* are brought together, in reversed position with respect thereto. The slots *n²*, *o²* within the hooks *n'*, *o'* are of such dimensions as to receive a locking element, which in the present instance is shown as a link *p* of a pendant support for the appliance.

With the receptacle *c* wired up and supported on the ceiling in the manner described in detail hereinbefore and with the conductor arms of the two halves *k*, *k'* of the improved plug wired up to the appliance in the manner described the method of connecting the plug electrically to the main wires *b* and supporting it mechanically within the receptacle should be apparent. Each of the conductor arms *l* is forced upwardly through the slots *c⁵* in the receptacle *c* and along the channels, such as *h³*, provided to receive them. With the two halves *k*, *k'* of the plug in some such position as is indicated in dotted lines in Fig. 1 and before forcing the terminal arms home the locking unit or link *p* is entered in the slots *n²*, *o²* of the sister hooks *n'*, *o'* and the hooks then brought together to the position shown in full lines in Fig. 1. Any pull on the locking element *p* will serve to wedge it more snugly between the hooks in such manner as to lock the respective conductor arms more securely in place within the receptacle. In removing the appliance the reverse operation is carried on, the locking element *p* being raised slightly within the diverging slots so as to permit the hooks to be forced apart. When the conductor arms are in position within the receptacle the weight of the appliance is carried by them. It will be observed that their ends may have points of rest in the horizontal portions *h³* of the channels *h²* so as to better distribute the weight of the appliance, although the wedging action of the arms within the curved channels is such as to afford an ample and secure support throughout. The pull of gravity on the appliance will serve to lock the arms securely within the receptacle and prevent positively the accidental withdrawal of the arms.

The scope of the invention will appear from the appended claims.

I claim as my invention:

1. An electrical connecting and supporting device for electrical appliances, including in combination a receptacle having terminals therein, a sectional plug having conductor arms to engage the terminals, respectively and hooks carried with the respective sections of the plug and adapted to receive in locking engagement therewith a supporting element for the appliance.
2. An electrical connecting and supporting device for electrical appliances including in combination a receptacle having grooves and terminals therein, a sectional plug having curved conductor arms to enter the grooves and engage the terminals, respectively, and hooks carried with the respective sections of the plug and adapted to receive in locking engagement therewith a supporting element for the appliance.
3. An electrical connecting and support-

ing device for electrical appliances including in combination a receptacle having entrance grooves and terminals therein, a sectional plug having oppositely extending conductor arms to enter the grooves, respectively for electrical and mechanical connection, and hooks carried with the respective sections of the plug and adapted to receive in locking engagement therewith a supporting element for the appliance.

4. An electrical connecting and supporting device for electric ceiling appliances including in combination a ceiling receptacle having reversely curved terminal slots therein, a sectional plug having reversely curved conductor arms to enter the slots, respectively, hooks having cam surfaces carried with the respective sections of the plug and adapted to receive in locking engagement therewith an element of the pendant support for the appliance.

5. Electrical connecting and supporting members for lighting appliances comprising curved conductor arms, complementary

plug sections carried by the conductor arms and hooks carried with the plug sections and adapted to receive in locking engagement therewith a supporting element for the appliance.

6. An electrical connecting and supporting member for lighting appliances comprising curved conductor arms, complementary segmental conical plug sections carried by the arms, and hooks having reversely curved meeting edges carried by the respective plug sections and adapted to receive in locking engagement with said meeting edges a supporting element for the appliance.

7. In an electrical connecting and supporting device in combination with a fixture stud, a receptacle, plates bolted thereto and having flanged ends, a bridge piece having keyhole slots to receive the flanged ends and extending angularly thereto and means to secure the bridge piece to the fixture stud.

This specification signed this 18th day of May A. D. 1920.

ERNEST CANTELO WHITE.
